UNITED STATES PATENT OFFICE.

MARC BIRKIGT, OF BOIS-COLOMBES, FRANCE.

TEMPLATE FOR GRINDING MACHINES.

Application filed June 26, 1925, Serial No. 39,802, and in Belgium July 14, 1924.

This invention relates, more particularly as regards their manufacture, to articles at least partly convexo-circular; and it relates more particularly (since it is in their case 5 that its application seems to be of the greatest importance), but not exclusively, among the said articles, to the templates to be used on the grinding machines for machining cam shafts such as those of the explosion 10 engines of the Hispano-Suiza type.

It has for its object chiefly to enable these articles to be manufactured in an accurate as well as quick manner.

It consists chiefly in using, as the device 15 for the machining of the convexo-circular portion of the articles of the kind in question, and also of their other portions, an arm pivoted on a frame and provided in such a manner with an article-holder, in its turn 20 such, that it should be possible to arrange on it the articles to be machined in such a manner that the centre of the convexo-circular portion with which they are to be provided, should be situated on the axis of rotation, of the said arm, and that consequently 25 it should be possible, by mounting the device thus constituted, level with a rotary tool in such a manner that the said axis of rotation and that of the said tool should be 30 parallel, and by swinging then the said arm towards the said tool, to arrive at the desired result which is reached when the article mounted on the said arm can pass freely the rotating tool during the swinging movement 35 or rotation in question.

Apart from this chief arrangement, it 40 comprises certain other arrangements which are preferably utilized at the same time and which will be hereinafter more explicitly referred to, namely an additional arrangement which in its turn consists:

In providing the blanks from which the articles of the kind in question are to be produced, with such a portion,

45 In providing similarly the devices to be used for the transformation of the said blanks into the latter articles, with a portion also such,

50 And in providing in a manner, also such, a tool adapted to be applied to the said portions when certain conditions are fulfilled,

That it should be sufficient—in order to give to the blanks when mounting them on the device to be used for the transformation,

the desired position in order that the said 55 transformation should be done with an absolute precision—to bring the said portions into such respective positions that the said instrument or tool could be exactly applied to them.

60 It relates more particularly to a certain method of application (that in which application is made to the manufacture of templates to be used on the grinding machines for machining cam shafts such as 65 those of the explosion engines of the Hispano-Suiza type), as well as to certain methods of carrying out (which will be herein-after referred to) the said arrangements; and it relates more particularly still, by way of 70 new industrial products, to devices comprising the application of the said arrangements, to special elements suitable for building them, to articles obtained with such devices, 75 to apparatus (engines etc.) comprising similar articles, as well as stationary or moving installations (namely aeroplanes) comprising such apparatus.

And it will be in any case clearly understood from the additional description which 80 follows, as well as from the accompanying drawings, which additional description and drawings are of course given chiefly by way of example.

Figure 1 of the said drawings shows in 85 elevation, partly in vertical section, a device built according to the invention, the arm which it comprises being shown there in two symmetrical positions relatively to a certain central position which can be given 90 to it.

Figure 2 shows in elevation the said device, its arm and the article-holder with which the said arm is provided, being shown there, the arm in its central position, and the 95 article-holder in two different positions.

Figure 3 shows in plan, partly in horizontal section, the same device, one of the two disappearing fingers with which it is provided, being shown therein in its two end 100 positions.

Figure 4 shows in end view, on a comparatively larger scale, an article such as those to the machining of which the invention chiefly relates, namely a template suitable for being used for the grinding of the cam shafts of the explosion engines of the Hispano-Suiza type.

Figure 5 shows in cross section, on the same scale, the blank of such a template in the course of machining.

Figure 6 shows in elevation, partly in vertical section and with parts broken off, and on a scale between that of Figures 1-3 and that of Figures 4 and 5, certain of the constituent parts of the said device, which are shown therein in the positions to be given, when a template blank is being mounted on the same device, both to the said parts and to the said blank.

Figures 7 and 8 finally show, in a manner similar to Figures 1 and 2, the same device in two special positions of certain of its parts.

According to the invention and more particularly according to that of the methods of its application, and to those of the methods of carrying out its various parts to which it seems that preference should be given.

When it is intended to build for instance a template or master cam that can be utilized for the grinding—with the assistance, for instance also, of a grinding machine such as that to which relates my copending application Serial No. 39,803, filed of even date herewith—of cams of cam shafts of explosion engines of the Hispano-Suiza type,

That is to say, a master cam comprising like the cams just mentioned and as shown in Figure 4,

On the one hand, and in order to constitute its raised portions or bosses, that is to say the operative part, two convexo-cylindrical elements 'AB' and 'AB'' not concentric with its axis O, but symmetrical relatively to a plane 'XOX' comprising the generatrix A which is common to them, as well as the said axis O,

And, on the other hand, and in order to constitute its low portion, a concavo-cylindrical element 'CC' concentric with the axis O and having also as the plane of symmetry the said plane 'XOX',

And then two concavo-cylindrical elements 'CB' and 'C'B'' having their respective axes comprised in a plane which is not only parallel to the plane 'YOY' at right angles to the preceding one and comprising the said axis O, but also situated at such a distance above the latter that the said elements join the preceding element, and that each of them intersects the corresponding ramp or

boss 'AB' or 'AB'' at a fairly sharp angle along that of the generatrices B or B' of the said ramp or boss, along which the latter is intersected by that of the planes at right angles to it, which comprises the axis O,

Or, more exactly, a template comprising two similar master cams secured to one end the same spindle and arranged at a certain angle relatively to each other,

Instead of proceeding to that end in the usual manner, for the same purpose is used,

on the one hand, a special device, and on the other hand, special blanks which are made in the manner that will be described or in a similar manner, it being assumed as regards the said device that the rotary tool jointly with which it is desired to use it, is the grinding wheel α with a horizontal axis a^o of a grinding machine.

As regards, first of all, the said special device, the proceeding for making it is preferably as follows:

A frame b is built in such a manner that it comprises a shoulder which allows it to be mounted on the bed (not shown) of the said grinding machine, and that it comprises in a similar manner bearings b^1 such that, as soon as the frame in question is mounted in the manner stated, their axis c^o should be parallel to the said axis a^o as well as on the same level, and that moreover they could be used for turning or rotating the arm which will be referred to in a moment.

An arm c is built in such a manner that it could be pivoted to the said support by means of the said bearings, namely in addition to a spindle b^2 .

That it should itself comprise a pair of bearings c^1 such that it should be possible to mount in them in such a manner the spindle d of the blanks to be converted into the templates to be obtained, that the axis d^o of the said spindle should then be not only parallel to the axis c^o of the bearings b^1 , but also at a distance from the latter axis, equal to the difference between the radius of curvature of the cams or bosses to be produced on the template, and the distance which, as soon as this cam or boss is ground, must separate it from the said axis;

That it should similarly comprise, and in order to complete the article holder which is partly constituted by the said pair of bearings, a system of locking concentric with the said bearings and adapted to allow, as soon as the spindle d of a blank is mounted in the manner just stated, to fix the said spindle in the angular position that may be desired;

And that it should comprise, or could receive, at least one operating lever c^2 by means of which it could be turned at will as soon as it is pivoted in the manner stated.

And these various elements are assembled together.

And concerning then the said special blank, they are preferably made in such a manner that each of them has the shape of a spindle d comprising, situated on it at a certain distance apart, two cylindrical thickened portions each extended by a kind of wedge d^1 or d^2 ,

These thickened portions being such that their radii should be equal, both, to the distance which after the grinding of the cams AB and AB' into which the faces of the

wedges d^1 and d^2 are to be converted, must separate the terminal ribs B and B' of the said cams from the axis O of the template which is to be provided with them.

5 And the said wedges being such that, first of all, the two faces of each of them should be tangent to the corresponding cylindrical boss or thickened portion, this along the generatrices of the latter, with which must coincide the said ribs or edges B and B', that, thereupon and consequently, they should be each of a desired angle (which is of course not the same for both), and that finally they should be set relatively to each 10 other to the same angle as the two master cams with which the said template is to be provided.

The device is installed in a suitable manner on the bed of the grinding machine 20 jointly with which it is to be used; the grinding machine, the grinding wheel or disc α with which it is to be provided, is at the same time chosen in such a manner that it should have a radius at the outside equal to 25 that of the concavo-cylindrical elements with which the template to be obtained is to be provided.

The lever c^2 of the arm c is operated so 30 that the latter is facing the top of the grinding disc α .

The spindle d of a blank is placed into the bearings c^1 , and the system of locking added to them, is operated in such a manner that the said spindle is locked in the desired position, that is to say in such a position that, assuming that it is question first of all of 35 grinding the cam AB of the wedge d^1 , the face of the latter to be converted into the said cam, should be at right angles to the plane formed by the axes c^0 and d^0 .

The grinding disc α is brought, if it is not there already, level with the said wedge d^1 ; it is moved back to a sufficient extent to prevent it from at once acting on the said 45 wedge, and it is then started.

It is given then a slight advance, and, this having been done, the transformation of the said face proceeds, for which reason:

The arm c is turned by means of the lever 50 c^2 , towards the grinding disc α , and the latter having been thus brought into position to bite the said face, it begins the work to be executed, this whilst the turning movement in question is continued until the said face 55 has been caused to pass the grinding disc;

The arm c is returned to the position which had been given to it right in the beginning, the advance of the grinding disc is slightly increased, and it is caused to perform a new 60 operation, this again with the turning of the arm c as before;

And this is continued until, the advance given to the grinding disc being sufficient, the transformation to be effected is 65 completed.

The transformation of the second face of the said wedge d^1 is then at once proceeded with, for which reason: first the system of locking of the spindle d is rendered inoperative; the latter is given an angular movement that should be given to it; the spindle d is again locked in position; and the operation is continued in the same way as before. 70

The rest of the master cam, the cams or bosses of which have been just made is then 75 machined for which reason: the disc α is first moved back to a fairly large extent; the arm c is brought into horizontal position, that is to say such a position that the axis d^0 of the spindle d is in the horizontal plane 80 formed by the axes a^0 and c^0 , and the said arm is locked in this position.

The system for locking the spindle d is rendered inoperative so as to enable the said spindle to turn in the bearings c^1 or, still 85 better, the said system is made such that the said rotation can be imparted to the spindle d only between two limits, namely between the position (which is shown in Figure 8) 90 required for the making of the element BC, and the position (symmetrical of the latter relatively to the horizontal plane passing through the axis d^0 of the spindle d^0) required for the making of the element B' C'; 95

The spindle d is placed into the first of these positions; the disc is given the desired advance so as to enable it to start working the said element B C;

It is caused actually to start the said work, and whilst it is working, the spindle d is 100 slowly rotated about itself in the desired direction (namely in the anti-clockwise direction, assuming that one is looking at the said spindle from the side shown in the drawings) in order to start simultaneously 105 the machining both of the element C C' and of the element C' B', the rotation in question, namely that to be imparted to the spindle d , being to that end continued until, and only until, the moment when the said spindle is 110 brought into the second angular end position;

A new advance is then given to the grinding disc, then a rotation in the direction opposite to that of the preceding one, that is to say a new operation begins; 115

This is continued until the transformation to be effected on the cylindrical boss which is extended by the wedge d^1 , is in its turn finished.

The transformation of the wedge d^2 and 120 of the cylindrical boss of which it forms extension, is then proceeded with in the same way.

After which it is sufficient, in order to 125 finish the template, to round off the top of each of the two master cams formed in the same, which can be done in any suitable manner, because, since it is question of making a cam of the type hereinbefore described, the shape given to its top is of small 130

importance, whereas on the contrary the position of its edges or ribs B and B' as well as the shape given to the portions immediately adjoining the said edges or ribs, play the most important part in the working of the engine which is to be provided with the said cam.

And either one is content, as regards the device and the blanks to be machined by means of the latter; to make them as hereinbefore set forth; or and still better, in addition and for the said making, are used additional means or arrangements which make it possible to give so to say automatically to the various parts the positions in which they have to be placed, according as it is desired to obtain one result or another, for instance and assuming that it is question as before of obtaining templates such as those described in the foregoing, means and arrangements such as the following.

The utilization, for constituting the locking system with which, in addition to the bearings c¹, the article holder is to be provided that is to say in the present case the blank holder, of a whole constituted:

By the free end of a kind of chuck built in such a manner that it is possible to secure to it with one of their ends the spindles d¹ of the blanks pivoted in one of the bearings c² forming a hub for a disc e comprising in its turn, distributed along the edge of its front face, three graduated scales e¹, in vertical line with which are provided a certain number of holes e⁰;

By three quadrants f which can be brought into exactly determined positions, level respectively with the first, second and third of the said scales,

Each of them comprising to that end first a datum mark f¹, then two elongated eyes or openings f⁰, each of which can receive the stem of a bolt g passed through one of the said holes e⁰;

And each of them comprising moreover a kind of a hollow handle f² designed in such a manner as regards its free end, and supplemented, also in such a manner, by a pin h mounted in it jointly with a spring.

That, on the one hand, the front end of the said pin projects in normal time under the action of the said spring beyond the front face of the corresponding quadrant:

And that, on the other hand it is possible, by exercising a pull on the rear end of any one of the three pins h, and by imparting to it then a certain angular movement, to keep its said front end on this side of the said front face of the corresponding quadrant:

By a hole h⁰ provided in such a manner in a suitable portion of the arm c, that, by introducing into it one of the pins k, the disc e can be locked relatively to the arm c;

By two fingers i pivoted in such a manner, one on the upper face, and the other on the

lower face of the arm c, that each of them can be placed at will either in the circular track or path followed by the pins h when they are, on the one hand, in operative position, that is to say projecting as stated, and on the other hand, not locked in the hole h⁰, and when the whole constituted by the disc e and its accessories, is turned about itself,

Or be withdrawn from the said path,

The operative portions i¹ of the said fingers being preferably, and as will be assumed throughout the following description, made distinct from the said fingers themselves, and mounted on the same for instance by means of screws, so as to enable the height to be regulated at will;

The whole making it possible in fact, and assuming that the initial mounting of the spindle of the blank has been suitably carried out, to give to the said blank, and this in a reliable manner and with the most absolute precision, the various angular movements required for transforming it as necessary.

Such a construction of each blank that it comprises a mechanical portion which, as will be assumed in the following description, can be constituted simply, in the case more specially considered, by one of the flat faces of its wedges d¹ and d²;

Concurrently, such a construction of the device itself that the upper face of its arm c comprises also a machined portion c³; and concurrently again, such a construction of a kind of angle part j that, as soon as the position of the pins h on the disc e has been adjusted, and one of the pins (the one required) caused to project in the hole h⁰ and as soon moreover as the spindle d of a blank has been introduced into the chuck of the said disc e, it should be possible to give to the said blank, before locking it by means of the said chuck, the position in which it is to be secured by the same chuck to the disc e in order that the said initial mounting should be the required one.

And the addition to the device, of means suitable, some of them to limit at will the movements that can be imparted to the arm c, and the others, to lock it in a certain position, more particularly that in which it is horizontal, which means could be namely constituted:

The first ones by a cylindrical guide or slot b² having for its axis the spindle b¹, provided on the lower portion of the frame b, and by a section of spindle k, adapted to be placed in such a position as may be desired along the said slot and to form then a stop itself adapted to limit the movement of the arm c in the downward direction;

And the second means, by a latch, or locking bolt l mounted so that its axis is horizontal, on the frame b, and by a hole c⁴ provided in the arm c in such a manner that it can receive the said locking bolt l, and that

the said arm is then horizontal, that is to say in the desired position in order that the axis of its bearings c^1 should be in the horizontal plane formed by the axes c^0 and c^0 .

Assuming that a device and blanks have been constructed exactly as just described, and moreover and as shown in the drawings, in such a manner that one of the faces of one of the wedges, and the non-corresponding face of the other, are in one and the same plane (which corresponds to the case of cams for obtaining the beginning of admission at the very end of exhaust) and that it is desired to manufacture with their assistance a series of templates of the kind described, it is sufficient to proceed in the following manner:

First of all, to regulate or to adjust in such a manner the respective angular positions of two of the three quadrants, for instance of those marked by 1 and 2 at the same time as by f , that

As soon as the pin h of the quadrant 1 has been brought into the hole h^0 (see Figure 1), and the spindle d^1 of a blank adjusted in position by means of the angle part j (see Figure 6), and then secured by means of the chuck in the said position which corresponds to the grinding of the cam AB of one of the master cams to be obtained.

It should be possible, in order to give the said blank the exact desired position for the grinding of the cam AB' of the same master cam, to content oneself to bring the pin h of the quadrant 2 to engage in its turn with the hole h^0 (see Figure 7);

To proceed in the same way for the regulation of the angular position of the quadrant 3 which—owing to the fact mentioned a moment ago that two of the faces of the wedges d^1 and d^2 are in one and the same plane—can be used concurrently with the quadrant 1 without having to alter the initial adjustment of the latter, in order to make the two cams of the second master cam.

To regulate then the height of the operative portion i^1 of the fingers i in such a manner that, for the purpose of making the low portion of the master cams, it should be possible as soon as the arm c is locked in its horizontal position, simply:

As regards the first cam, to place the pin h of the quadrant 3 in inoperative position, and to turn the disc e in such a manner as to bring first the pin h of the quadrant against the bottom of the operative portion i^1 of the lower finger i (see Figure 8), and then the pin h of the quadrant 2 against the top of the operative portion i^1 of the upper finger i (Figure 2),

And as regards the second cam, to place the pin h of the quadrant 2 in inoperative position, and to turn the disc e in such a manner as to bring to bear first the pin h

of the quadrant 3 against the bottom of the operative portion i^1 of the lower finger i , and then the pin h of the quadrant 1 against the top of the operative portion i^1 of the upper finger i ;

After which, as will be understood by any expert without any further explanation the templates can be obtained in a sort of way mechanically, the absolute identity of all making it possible to obtain cams, in their turn absolutely identical with each other, whatever be the template that has been used for grinding them, the only condition to be fulfilled to that latter end, that is to say in order that the cams themselves should be absolutely identical, being that the grinding machine as well as the device hereinbefore described, are of high precision.

It goes without saying, and it follows besides from the preceding, that the invention is by no means limited to that of the methods of its application, or to those of the methods of construction of its various parts, which have been more particularly specified; but comprises on the contrary any modifications, namely: those in which it would be applied for direct obtainment of cams or other articles; those in which it would be carried out as previously, but by proceeding in such a manner that the bearings c^1 instead of forming an integral portion of the arm c , would be provided on a part distinct from the said arm, and secured to the latter in such a manner that it should be adjustable relatively to it, more particularly so as to enable the distance between the axis d^0 and the axis c^0 , that is to say, the length of the arm c to be modified at will;

Those in which, in order to constitute the grinding machine with which the device is to be combined for its utilization, would be used a grinding machine of the kind of those, the grinding disc of which is exposed to the action of a means tending to keep it in a certain maximum advance position and enabling it to move back when it is forced to do so by the part to be ground by it;

And those in which the device would be completed by means adapted to render automatic certain, at least, of the movements to be imparted to its elements for utilizing it.

Claims:

1. Apparatus for making articles which are partially convexo-circular in shape comprising a pivoted arm, means on said arm for holding the article of work, a suitably divided plate connected to the article and provided with projecting pins, and means on said arm to cooperate with said pins whereby the article of work may be non-rotatably fixed in a predetermined position with respect to said arm or the article may be rotated through a predetermined angle during machining, such angle being pre-¹³⁰

- 6 determined by the relative position of said pins.
2. An apparatus of the class described comprising in combination, a fixed frame, 5 an arm pivotally mounted on said frame, means operable to rotate said arm, a rotatable shaft mounted on said arm toward the free end thereof, a disc associated with said rotatable shaft, and means for locking said disc to prevent angular displacement thereof relatively to said arm.
3. An apparatus of the class described comprising in combination, a fixed frame, an arm pivotally mounted on said frame, 10 means operable to rotate said arm, a rotatable shaft mounted on said arm toward the free extremity thereof, a disc connected to said rotatable shaft, means for locking said disc to prevent angular displacement thereof relatively to said arm, and means for locking said arm to prevent angular displacement thereof relatively to said fixed frame.
4. An apparatus of the class described comprising in combination, a fixed frame, 15 an arm pivotally mounted on said frame, means operable to oscillate said arm, a ro-
- tatable disc mounted toward the free extremity of said arm, locking means operable to prevent angular displacement of said disc relatively to said arm, said locking means being mounted in adjustable angular relation to said disc, and means for rigidly connecting said locking means to the disc in predetermined adjusted angular relationship. 20
5. An apparatus of the class described comprising in combination a fixed frame, an arm pivotally mounted on said frame, means operable to oscillate said arm, a disc rotatably mounted toward the free extremity of 25 said arm, locking means operable to prevent angular displacement of said disc relatively to said arm, means for rigidly connecting said locking means to the disc in predetermined adjusted angular relation, and means for locking said arm to prevent oscillation thereof relatively to the fixed frame. 30
